TRAVEL TRAILER

Richard M. Johnson, Morrison, Ill. 61270

Filed June 5, 1967, Ser. No. 8,939

Term of patent 14 years

(Cl. D14—3)

FIG. 2

FIG. 3

FIG. 3

FIG. 4

FIG. 5

FIG. 5

FIG. 7

FIG. 1 is a rear perspective view of a travel trailer incorporating the concepts of applicant's design illustrated in an open position;

FIG. 2 is a front perspective view taken opposite the view of FIG. 1;

FIG. 3 is a side elevation;

FIG. 4 is a front elevation;

FIG. 5 is a rear elevation;

FIG. 6 is a front perspective view of the trailer illustrated in a travel or closed position; and,

FIG. 7 is a rear perspective view taken opposite the view of FIG. 6.

The dominant features reside in the solid line portions.

I claim:

The ornamental design for a travel trailer, substantially as shown and described.
